UNITED STATES PATENT OFFICE.

ALFRED WYATT, OF KANSAS CITY, MISSOURI, ASSIGNOR OF ONE-THIRD TO SAMUEL J. COCHRAN AND ONE-THIRD TO FRANK A. COCHRAN, BOTH OF KANSAS CITY, MISSOURI.

ELECTROMAGNETIC SOUND-WAVE-INTENSIFYING DEVICE.

Application filed April 10, 1922. Serial No. 550,892.

To all whom it may concern:

Be it known that I, ALFRED WYATT, a citizen of the United States, and resident of Kansas City, county of Jackson, State of Missouri, have invented a certain new and useful Improvement in Electromagnetic Sound-Wave-Intensifying Devices, of which the following is a complete specification.

The present invention relates to sound amplifying devices, and aims to provide an improved construction of this type whereby the sound waves generated by any of the common forms of sound reproducing or transmitting devices may be greatly intensified in the course of their transmission to the point of final reproduction by means of the ordinary forms of amplifying or loud speaking instruments.

Accordingly, the invention comprises a vibratory diaphragm electrically actuated by means of an electromagnet in circuit with a sound wave producing or transmitting instrument, together with means for mechanically transmitting the vibratory action of said diaphragm to an electric circuit including the amplifying or loud speaking instrument which finally reproduces the original sound waves or tones, through the medium of a suitable microphone element forming a part of the latter circuit.

With the foregoing general object in view, the invention will now be described by reference to the accompanying drawing illustrating one form of construction which I have devised for embodying the proposed improvements, after which those features deemed to be novel will be particularly set forth and claimed.

In the drawing—

Figure 1 is a face view showing one end of an amplifying device constructed in accordance with the present invention;

Figure 2 is a plan view of the same;

Figure 3 is a view similar to that shown in Figure 1, but with the face plate removed for disclosing the interior of the device; and

Figures 4 and 5 are sectional views, taken on the lines IV—IV and V—V, respectively, of Figure 3, Figure 5 being on an enlarged scale.

Referring now to said drawing in detail, this illustrates the improved construction as comprising a pair of housing sections 6, 7, for enclosing the operative parts of the device, the section 6 being of smaller diameter

than the housing section 7, and attached thereto by means of screw threads as clearly shown in Figures 4 and 5, with the base portion of the section 6 acting as a partition 8 and thereby dividing the space within the housing structure into two compartments 9, 10. The open portion of the housing section 6 is closed by means of a screw cap member 12 provided with suitable vent openings 14 and serving to support a suitable diaphragm member 15 across the outer side of the compartment 9, said diaphragm being supported for proper vibratory action by having its margin clamped between a pair of rings 16, as clearly shown in Figure 5. By this means the diaphragm 15 is held in position to act as the armature for an electromagnet of the double horse shoe type, and comprising a pair of coils 17 connected with terminals 18 adapted to be included in a circuit with the sound producing or transmitting instrument (not shown), such as the reproducer of a talking machine, or the receiving instrument of a wireless system. The coils 17 of the electro-magnet are carried upon pole pieces 19 formed as parts of the angle bars 20, the outer ends of which are connected by screws 21 to semi-circular ring sections 22, and the latter supported by insulated screws 23 threaded into the partition member 8 between the compartments 9 and 10, a set of three of these screws 23 being provided as shown in Figure 3.

To the diaphragm member 15 is centrally connected a rod or stem 24 extending inwardly between the coils 17 and through an opening 25 in the partition 8 for connection with one of the carbon elements of a microphone structure provided in the compartment 10 (see Figure 5). This microphone is of ordinary form, and comprises a shell or housing member 26 having a stem 27 adjustably clamped by means of a screw 28 within a bushing 29 carried in the outer face of the housing section 7 and insulated therefrom by a collar 30 and washer 31 embraced by a clamping nut 32 on the inner end of the bushing 29. Within the open portion of the shell 6 is threaded a flanged ring 33 provided with a mica diaphragm element 34, the middle portion of which is clamped between one of the carbon discs 35 and a metallic disc 36 to which the stem 24 is centrally connected, the microphone structure being so carried as to align its

axis and said stem 24 centrally with the diaphragm member 15. The diaphragm 34 is spaced by an insulating ring 37 from the other carbon disc 38, and the usual granulated carbon 39 is interposed between the said carbon discs 35 and 38. The carbon disc 35 is electrically connected by means of a conductor 40, with a suitable binding post 41, while the other carbon disc 38 is similarly connected by means of a conductor 42 with a second binding post 43, to which posts may be attached the conductors 44 of an electric circuit designed to include any suitable form of amplifying or loud speaking instrument (not shown) at the point where the sound waves or tones are to be finally reproduced after having been intensified by the device of the present improvement.

It is believed that the operation of the instrument will be clear from the foregoing, the influence of the original sound waves as transmitted through the electric circuit including the coils 17 acting to produce fluctuations in the magnetic action of these coils, and thereby causing the diaphragm member 15 to respond to the varying action of the coils and hence reproduce the vibrations as transmitted from their source; the vibrations of the diaphragm member 15 are transmitted directly to the microphone structure, and by its action vastly intensified, and these intensified vibrations directly transmitted through the circuit connections 44 to the amplifier or other instrument designed for the final reproduction of the sound waves or tones. The advantage of the improved construction lies in the fact of the microphone instrument being directly connected to a diaphragm structure to which the sound vibrations are electromagnetically transmitted from the source, so that the full force of the vibratory action is transmitted to the microphone and

the intensifying action of the latter maintained at a maximum. This direct association of the microphone and the electromagnetic transmitting device is of such a character as to be readily embodied in a simple and compact instrument, which may be used to great advantage in the amplification of sound vibrations as produced either by the ordinary type of phonographs or wireless receiving sets, and the intensified vibrations transmitted to any desired commercial form of amplifying or loud speaking instruments.

While I have illustrated and described what I now regard as the preferred form of construction for embodying the invention, I desire to reserve the right to make all such changes or modifications as may fairly fall within the scope of the appended claim.

What I claim is:

A sound amplifying device comprising a pair of housing sections having a partition forming separate housing compartments, an electromagnet supported by said partition within one of said compartments and having terminals adapted for connection with an electric circuit including sound producing means, a vibratory diaphragm carried by the housing section enclosing said electromagnet in position for forming the armature for said electromagnet, a microphone supported by the other housing section within the other of said compartments and in central axial alignment with said diaphragm and having an operative connection extending centrally through said partition to the center of said diaphragm, said microphone having terminals adapted for connection with an electric circuit including a loud speaking or amplifying instrument.

In witness whereof I hereunto affix my signature.

ALFRED WYATT.
